(57) **CLAIM**

The ornamental design for a pouch for oral use as shown and described.

DESCRIPTION

FIG. 1 is a perspective view of a pouch for oral use showing my new design;

FIG. 2 is a cross sectional view thereof, taken in a plane perpendicular to a longitudinal dimension of the pouch for oral use, said plane shown in FIG. 3;

FIG. 3 is a top plan view thereof;

FIG. 4 is a left side elevational view thereof;

FIG. 5 is a rear elevational view thereof;

FIG. 6 is a bottom plan view thereof;

FIG. 7 is a right side elevational view thereof; and,

FIG. 8 is a front elevational view thereof.

The broken lines in the drawings having consistent dash lengths (dash-dash-dash) depict portions of the pouch for oral use that form no part of the claimed design.

The jagged lines having inconsistent dash length (dash-dot-dash) in FIGS. 1, 3, 4, 6, and 7 show a symbolic break along a length of the pouch for oral use, and the appearance of any portion of the pouch for oral use between the break lines forms no part of the claimed design.
